[57] CLAIM

The ornamental design for a range finding device for close-up, as shown and described.

DESCRIPTION

FIG. 1 is a front elevational view of a range finding device for close-up showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top and left front perspective view thereof;

FIG. 8 is a top and left front perspective view thereof wherein the rod is in a broken down and received position.

FIG. 1

FIG. 2

FIG. 3

FIG. 4

FIG. 7

FIG. 8
